UNITED STATES PATENT OFFICE.

SAMUEL W. PEARCE AND RICHARD H. PEARCE, OF TUSHKA, OKLAHOMA.

TIME-CONTROLLED DEVICE.

1,129,596.

Specification of Letters Patent.

Patented Feb. 23, 1915.

Application filed April 11, 1914. Serial No. 831,228.

To all whom it may concern:

Be it known that we, SAMUEL W. PEARCE and RICHARD H. PEARCE, citizens of the United States, residing at Tushka, in the county of Atoka and State of Oklahoma, have invented certain new and useful Improvements in Time-Controlled Devices, of which the following is a specification, reference being had to the accompanying drawings.

This invention relates to certain improvements in time controlled devices and has relation more particularly to a device of this general character especially designed and adapted for use as an annunciator; and an object of the invention is to provide a novel and improved device of this general character adapted to operate a signal at a predetermined time.

The invention has also for its object to provide a novel and improved device of this general character adapted to be operatively connected with a moving part of a conventional clock and provided with regulatable means whereby a signal may be caused to operate at any predetermined period of time.

The invention consists in the details of construction and in the combination and arrangement of the several parts of our improved time controlled device whereby certain important advantages are attained and the device is rendered simpler, less expensive and otherwise more convenient and advantageous for use, all as will be hereinafter more fully set forth.

The novel features of the invention will be carefully set forth in the appended claims.

In order that our invention may be the better understood, we will now proceed to describe the same with reference to the accompanying drawings, wherein—

Figure 1 is a view in rear elevation of a conventional clock, showing an annunciator constructed in accordance with an embodiment of our invention in applied position thereon; Fig. 2 is a view in side elevation of the device as illustrated in Fig. 1; Fig. 3 is a view somewhat similar to Fig. 1 but showing our improved attachment in an inoperative position relative to the clock proper; Fig. 4 is an enlarged fragmentary elevational view of our attachment, with the controlling disk and rear plate removed; Fig. 5 is a sectional view taken substantially on the line 5—5 of Fig. 1; Fig. 6 is a view

similar to Fig. 5, but showing the contact in an inoperative position; Fig. 7 is a fragmentary view in perspective of the striking hammer herein included; Fig. 8 is a fragmentary elevational view disclosing the means herein included for maintaining the trip, forming part of our present invention, against release; Fig. 9 is a fragmentary sectional view taken through the central portion of our attachment and the rear plate of the clock, disclosing the form of connection, herein included, between the center staff of the clock and the central shaft of the attachment; Fig. 10 is a sectional view taken substantially on the line 10—10 of Fig. 9; and Fig. 11 is a sectional view taken substantially on the line 11—11 of Fig. 9.

As disclosed in the accompanying drawings, 1 denotes a clock of any conventional form but herein disclosed as an ordinary alarm clock including the bell 2. These parts may be of any ordinary or preferred construction and form no part of our present invention, except the center staff 3 thereof which projects beyond the rear face of the clock 1 and has its extremity angular in cross section, as indicated at 4, and more particularly shown in Fig. 9, for purposes which will be hereinafter more particularly explained.

5 denotes the forward plate of our attachment which is substantially of the same dimensions and configuration as the adjacent portion of the clock 1 and is hinged 75 connected with such clock, as indicated at 6, which hinge being so positioned as to permit the plate 5 to be swung substantially in a horizontal plane, and diametrically opposed to the hinge 6 is a conventional latch 90 7, herein shown as carried by the clock proper and adapted to hold or maintain the plate 5 in operative position relative to the clock proper.

Operatively connected to and maintained 100 in spaced relation with the plate 5 through the medium of the posts 8 is the rear plate 9 of a diameter less than that of the plate 5. Operatively supported between the plates 5 and 9 is the shaft 10 having fixed thereto 105 the toothed gear 11 and with such gear and shaft coacts the driving spring 12 of our improved attachment, such shaft 10 being projected forwardly of the plate 5, as is particularly shown in Fig. 3, and such 110 projected portion is provided with the button 12^a, whereby such shaft may be ro-

tated with convenience for winding the spring, in a manner which is believed to be clearly apparent to those skilled in the art to which our present invention appertains. 5 The gear 11 meshes with a pinion 14 carried by the shaft 15 operatively supported by the plates 5 and 9, and such shaft 15 has fixed thereto the escape wheel 16 with which coacts in the general way the escape dog 17 fixed to the shaft 18 also operatively supported by the plates 5 and 9. The shaft 18 has projecting upwardly therefrom the alarm hammer 19 disposed on such an angle as to permit the head 20 thereof to engage 10 or strike the bell 2 when the wheel 16 is released and permitted to rotate under the action of the spring 12. The shaft 15 is also provided with a disk 21 having produced in its periphery the notch or recess 22 which is 15 adapted to accommodate the angular extension 23 of the trip lever 24 pivotally supported intermediate its length by the stub shaft 25 projecting inwardly from the plate 9, and the opposite extremity or tail 26 of 20 the lever 24 is adapted to be engaged by the striking hammer 27, herein disclosed as formed on the extremity of the spring arm 28 operatively engaged with the shaft 29 operatively supported between the plates 5 25 and 9. Also supported by the plates 5 and 9 is the rebound bar 30 with which the spring arm 28 is adapted to contact when 30 rocking movement has been imparted to the shaft 29, the return movement to the shaft 35 being imparted, as herein disclosed, through 35 the medium of the flat spring 31 suitably fixed to the shaft 29 and passing under the rebound bar 30, as is particularly shown in Figs. 4 and 7. It will be seen that as the 40 hammer 27 strikes the tail or lower extremity 26 of the lever 24, the angular portion 23 thereof will be retracted from within the recess 22 of the escape disk 21, and the hammer 19 will be caused to vibrate 45 until the lever 24, or more particularly the angular portion 23 thereof, again engages the recess 22 to hold the shaft 15 against axial rotation. In order that the angular portion 23 of the lever 24 will automatically 50 enter the recess 22, we disclose herein a flat spring 32 suitably anchored to the inner face of the plate 9 and having its free extremity bearing against such lever 24 intermediate its fulcrum and its angular extremity 23.

The shaft 29 is adapted to be initially rocked through the medium of mechanical means and for this purpose such shaft 29 is provided with the projecting finger 33 55 of a length to project beyond the periphery of the plate 9 and adapted to be engaged or contacted with in a manner to be herein-after more particularly referred to.

Rotatably supported by the plates 5 and 60 9 and at substantially their axial centers

is a central shaft 34, the inner extremity of which being provided with a socket member 35 endwise adjustable thereon and adapted to engage the angular portion 4 of the center staff 3 of the clock 1, whereby it will be seen that the central shaft 34 will be caused to rotate in synchronism with such center staff. By having the socket 35 capable of movement endwise of the shaft 34, it will be readily perceived that an adjustable connection between the shaft and staff is afforded to compensate for any variations in applying our attachment to the clock. As herein disclosed, the socket 35 is provided with the longitudinally directed elongated 75 slots 36 through which project the extremities of a pin 37 disposed through the shaft 31 and outward pressure is disposed upon such socket 35 through the medium of the expandible member 38 interposed between 80 the inner extremity of the socket member 35 and a suitable stop 39 produced on the shaft 34.

The shaft 34 is of such length as to project exteriorly of the rear plate 9 and has 85 loosely mounted for rotation upon its outer extremity the controlling or operating disk or wheel 40 having produced in its periphery the teeth or notches 41, for a purpose to be hereinafter more particularly set 90 forth. The shaft 34 intermediate the plate 9 and the disk or wheel 40 has fixed thereto the gear wheel 42 meshing with a gear wheel 43 mounted on a stub shaft 44 carried by the plate 9, and such shaft 44 is also provided 95 with a pinion 45 in mesh with a gear 46, herein disclosed as integrally formed with the disk or wheel 40 and disposed concentrically around the axis thereof. The ratio of the gears 42, 43, 45 and 46 is such that 100 the disk or wheel 40 will be caused to make one complete revolution upon eight revolutions of the center staff 3 on which the minute hand of the clock is mounted, as is a conventional arrangement. As herein disclosed, the wheel 40 includes the peripheral flange 47, and in detachable or adjustable engagement with such flange 47 are the contact members 48, such members being herein shown as formed of a single strand of material having their opposite end portions angularly disposed, as indicated at 49, to straddle or bridge the opposite marginal portions of such flange 48, the outer angular portion 49 being adapted to engage between certain of the teeth 41 in order to determine the time of engagement of the inwardly disposed projecting extremity 50 of such contact or member 48 with the finger 33, which contact or engagement causes the shaft 29 to be rocked whereby it will be perceived that at any predetermined periods of time the hammer 19 may be caused to vibrate to give a signal. The contacts or members 48 possess a certain degree of re- 110 115 120 125 130

siliency or flexibility, whereby they may be removed from or applied to the flange 47 with convenience and facility and in order to facilitate their manipulation, we find it 5 of advantage to have the intermediate portion of each of such members or contacts 48 bent to afford the substantially V-shape extensions or fingers 51 which serve as an operating handle and also permit the requisite 10 separation of the angular portions 49 when it is desired to either apply or remove the contacts or members. As herein disclosed, the notches or teeth 41 produced in the periphery of the disk or wheel 4, or more 15 particularly the flange 47 thereof, are adapted to be one hundred ninety-two in number, or each tooth being the equivalent of two and one-half minutes of time, whereby it will be readily perceived that the moment of 20 contact or engagement between the projected extremity 50 and the finger may be caused to occur at any predetermined time.

Our invention, as herein disclosed, is especially adapted for use in connection with 25 school rooms or the like when the session is divided into different periods and serves as an effective means whereby a signal may be given at the conclusion of each of the periods. It often occurs that occasions arise 30 which require that the signal be made inoperative, and for this reason we pivotally mount upon the inner face of the plate 9 the bell lever 52 adapted to have one extension engage the lever 24 and maintain the 35 angular extremity 23 thereof within the recess 22 of the wheel or disk 21 against the action of the hammer 27, the second extension of such lever 52 extending beyond the periphery of the plate 9 so that such lever 40 may be manipulated with convenience and facility. For convenience of description, the lever 52 may be termed a "cut off."

From the foregoing description, it is thought to be obvious that a time controlled 45 device constructed in accordance with our invention is of an extremely simple and comparatively inexpensive nature and is particularly well adapted for use by reason of the convenience and facility with which it 50 may be assembled and by reason of the effectiveness with which it performs its functions, and it will also be obvious that our invention is susceptible of some change and modification without material departure 55 from the principles and spirit thereof and for this reason we do not wish to be understood as limiting ourselves to the precise arrangement and formation of the several parts herein shown in carrying out our invention in practice.

While it is believed that the operation of our improved device is clearly apparent from the foregoing description, it may be well to state that the contact members 48 60 are positioned upon the wheel 40 in prede-

termined spaced relation in accordance with the times at which it is desired to cause the bell 2 to sound, and such members 48 are adapted to have their projecting extremities 50 contact with the projecting finger 33 carried by the shaft 29 so as to cause the hammer 27, after an extremity 50 has passed over the finger 33, to strike the tail 26 of the lever 24 to rock the same in such a manner as to retract the angular portion 23 of the lever 24 from within the notch 22 of the disk 21, whereupon the shaft 14 will be caused to rotate under the influence of the spring 12 and thus cause the hammer 19 to strike the bell 2 until one rotation of the shaft 15 has been completed, whereupon the angular portion 23 of the shaft 24 will drop within the recess 22 and hold the shaft 15 against rotation until the next following projection 50 operatively engages the finger 33.

We claim:

1. In combination with an alarm clock including a bell and having its center staff rearwardly projected, a plate hingedly connected with the clock and adapted to overlie the rear face thereof, a striking mechanism carried by the plate and adapted to contact with the bell of the clock, and means carried by the plate operatively connected with the projected portion of the center staff for controlling the operation of the striking mechanism.

2. In combination with an alarm clock including a bell and having its center staff rearwardly projected, a plurality of spaced plates, one of said plates being pivotally engaged with the clock and adapted to overlie the rear thereof, a striking mechanism operatively supported by the spaced plates and adapted to contact with the bell, a shaft rotatably supported by the spaced plates, said shaft and center staff being provided with coacting means whereby the same may be operatively connected, a disk loosely mounted on the shaft, means for operatively connecting the shaft and disk to cause the disk to rotate in unison with the shaft but at a different speed, and means carried by the disk coacting with the striking mechanism for controlling the operation of the striking mechanism.

3. In combination with an alarm clock including a bell and having its center staff rearwardly projected, a plurality of spaced plates, one of said plates being pivotally engaged with the clock and adapted to overlie the rear thereof, a striking mechanism operatively supported by the spaced plates and adapted to contact with the bell, a shaft rotatably supported by the spaced plates, said shaft and center staff being provided with coacting means whereby the same may be operatively connected, a disk loosely mounted on the shaft, means for operatively connect-

ing the shaft and disk to cause the disk to rotate in unison with the shaft but at a less speed, and means carried by the disk co-acting with the striking mechanism for controlling the operation of the striking mechanism.

4. In combination with an alarm clock including a bell and having its center staff rearwardly projected, a plate hingedly connected with the clock and adapted to overlie the rear face thereof, a striking mechanism carried by the plate and adapted to coact with the bell of the clock, means

carried by the plate operatively connected with the projected portion of the center staff 15 for controlling the operation of the striking mechanism, and auxiliary means for locking the striking mechanism against operation.

In testimony whereof we hereunto affix our signatures in the presence of two wit- 20 nesses.

SAMUEL W. PEARCE.
RICHARD H. PEARCE.
